UNITED STATES PATENT OFFICE.

WILLIAM KOLLER, OF WHITE PLAINS, NEW YORK.

EMBROIDERY-FRAME.

1,400,293.

Specification of Letters Patent. Patented Dec. 13, 1921.

Application filed July 23, 1920. Serial No. 298,337.

To all whom it may concern:

Be it known that I, WILLIAM KOLLER, a citizen of the United States, residing at White Plains, in the county of Westchester and State of New York, have invented certain new and useful Improvements in Embroidery-Frames, of which the following is a full, clear, and exact specification.

This invention relates to embroidery frames, and has for its object to provide improved means for accurately fixing each one of a series of similar patterns on as many pieces of cloth, each carried by a separate frame adapted to be placed in turn below the needles of an embroidery machine, whereby all of the pieces of cloth may be embroidered alike and so that the embroidery will accurately cover the desired design or pattern printed on each of said pieces of cloth.

20 The invention contemplates the provision of a plurality of cloth clamping and holding frames, each comprising upper and lower frame members between which the cloth is adapted to be clamped, a table over 25 which said frames are adapted to be successively moved on a track or guideway, a movable member carrying design or pattern locating points adjustable thereon and adapted to be brought into register with the 30 pattern or design on each of the pieces of cloth mounted on the several frames as the latter are brought successively below said points, means for releasing the cloth in each frame while it is below the pattern locating 35 points, and means for clamping said piece of cloth in its frame after proper adjustment according to said points to insure the proper location of the design or pattern with respect to said frame when placed in 40 the embroidery machine.

The invention will be hereinafter described in detail in connection with the accompanying drawings, which constitute part of this specification, and then more specifically defined in the claims at the end of the description.

In the accompanying drawings, wherein similar reference characters are used to designate corresponding parts throughout the 50 several views:

Figure 1 is a side elevation of a table with one of the frames supported thereon, and the pattern positioning member arranged above said frame, one manner of 55 connecting the parts of the frame together

and of mounting the pattern positioning member being shown.

Fig. 2 is a plan view of a portion of the table showing three of the frames mounted thereon, the middle one arranged below the 60 pattern positioning member.

Fig. 3 is a side elevation substantially like that of Fig. 1 except that the parts of the frame are connected up in a different way and the pattern positioning member is 65 differently mounted.

Fig. 4 is a plan view of the device as shown in Fig. 3.

Fig. 5 is a detailed view on a larger scale of the latch mechanism for locking the parts 70 of the frame together after the cloth has been adjusted thereon below the pattern positioning member, the position of the parts before locking, as when the cloth is being adjusted on the frame below said 75 positioning device, being indicated in dotted lines.

Fig. 6 is a detailed section through a part of the frame showing the shape of the clamping parts thereof.

Fig. 7 is a plan view of the lower part of one of the frames.

Fig. 8 is an under plan view of the upper part of a frame.

Fig. 9 is an end view of the positioning 85 member and the upper part of one of the frames showing the latch mechanism more clearly, and also the centering device.

Fig. 10 is a detailed section through the pattern positioning member showing how 90 the positioning points are adjustably attached thereto.

Fig. 11 is detailed sectional view of one bar of the upper part of the frame, and

Fig. 12 is a similar view of one bar of 95 the lower part of said frame.

The table 1 may be of any desired length and is equipped with tracks or rails 2 extending along its top transversely to the embroidery frames 3 which have guides 4 100 on their bottoms to fit over said tracks or rails 2 whereby the frames may be guided in predetermined position along the table from one end where the frames may be placed thereon to the other end from which 105 they may be removed for placing below the needles of embroidery machines, not shown.

Each frame, as shown in Figs. 7 and 8, comprises upper and lower clamping parts of substantially the same shape, the lower 110

part 5 having side bars and transverse bars 6 and 7, respectively, in the form of channels 10 communicating with one another, Fig. 7, and the upper part 50 having corresponding side bars 8 and transverse bars 9 having continuous ribs 11 to fit in said channels 10 of the lower part for clamping a piece of cloth to be embroidered, as indicated at 12 in Fig. 6. In order to insure a tight gripping action on the cloth between said rib and channel, the upper part carrying the rib may be covered with a layer of rubber 13, Fig. 11, or other suitable material which will also prevent injury to the cloth.

As shown in Figs. 1 and 2, the lower part or clamping member 5 of each frame has downwardly offset rearward extensions 14 to its side bars 6, said extensions being provided with upwardly extending arms 15 to the upper ends of which the upper clamping member 50 is hinged at 16 by extensions 17 of its side bars 8 which extend beyond the hinges 16 and have their extremities connected to the extremities of the extensions 14 of the lower clamping member by springs 18 which automatically raise the upper clamping member away from the lower member when released at their front ends as will be later explained.

In Figs. 3 and 4 a modified form of connection between the rear ends of the clamping parts of the frame is shown in which the extensions of the side bars of said parts do not extend beyond the hinge 19 and a bowed spring is interposed between said extensions in advance of the hinge of each pair of extensions, as best seen at 20 in Fig. 3. These bowed springs 20 have the same action as the springs 18 of the other form of the device just described, that is, they automatically raise the upper clamping member away from the lower clamping member of the frame when said members are released at their front ends.

The two clamping members of each frame may be latched together at their front ends by means of a hook-shaped latch 21 hinged at 22 to the front end of the upper clamping member 50 and adapted to have its lower hooked end take under the front end of the lower clamping member 5 as shown in Figs. 1, 3, 5 and 9. Said latch has an outstanding lug 23 against which a spring 24 carried by the upper clamping member bears for automatically moving the latch into locking position when the members of the frame are brought together. The latch also carries a rigid pin or arm 25 extending substantially horizontally therefrom, when said latch is in vertical locking position, for operating the same as will be hereinafter explained.

At one point on the table a rearwardly extending bracket 26 is secured and to said bracket the pattern positioning member 27

is hinged, said member extending forwardly across the table above the frames 3 and adapted to rest on blocks 70 for spacing it above the member 50. As shown in Figs. 1 and 2, the member 27 is hinged at 28 to an upstanding arm 29 on the bracket 26 through an intermediary horizontal link 30 which is in turn hinged at opposite ends to a downwardly extending stud 31 on the member 27 and a vertical link 32 which is also pivoted to the member 27 at 33 and to a treadle 34 at 35. The rear extremities of the member 27 and bracket 26 are connected by a spring 36 which automatically raises the member 27 and holds it above the embroidery frames except when the treadle is pressed down, said treadle operating through the links 32 and 30 to swing the member 27 downward over said frame. Lateral swinging of the member 27 is prevented by a guide arm or bracket 37 on the rear end portion of said member engaging a slot 38 in a standard 39 attached to the bracket 26.

The hinge structure for the member 27 as shown in Figs. 3 and 4 is similar to that just described except that the rear end of the member 27 is curved downward at 40 and connected directly to the horizontal link 30, thus dispensing with the lug 31 of Fig. 1, and the spring 41 for raising said member is connected to said curved end of the latter at the point of hinge connection thereof with said link. In this form of the invention the guide arm or bracket 42 for preventing lateral swinging of the member 27 is connected to the bracket 26 and the slotted standard with which said arm engages is secured to the member 27 as shown at 43.

The member 27 has a slot 44 in the portion thereof disposed directly over the middle portion of the frame positioned below it on the tracks of the table, and in said slot there are adjustably secured a plurality of pattern positioning points or devices 45. As best shown in Fig. 10, two of these positioning points are preferably carried by each of a plurality of clamping bolts 46 fitted to slide in the slot 44 and adapted to be clamped in adjusted positions therein by a nut 47 on the lower end of each bolt coöperating with a thumbhead 48 on the upper end of said bolt. The positioning devices have shanks 49 with eyes 51 to fit around the bolts and be clamped in adjusted positions thereon when the nuts 47 are tightened up. By this means the several positioning devices may be adjusted so as to bring their points in position to locate the main points in any desired design or pattern to be embroidered on the cloth mounted on the frames, which design or pattern is marked on the cloth before the same is placed on the frames as already explained.

The front end of the member 27 extends forwardly beyond the frames 3 and said ex-

tending portion has a slot 52 therein through which the end of the pin or arm 25 for operating the latch for the frames may extend, as best shown in Fig. 5. Another slot 53 is formed in said front end of the member 27 in advance of the slot 52, and through said slot 53 a bolt 54 extends for connecting a slide 55 thereto. Said slide has an upstanding finger piece 56 at its front end for moving it forward, and to its rear end a spring 57 is attached for automatically moving the slide rearward when the finger is removed from said finger piece. The rear position of said slide may be determined by a block 58 secured to the member 27 and by the bolt 54 engaging the rear end of the slot 53. The slide 55 has a slot 59 therein adapted to register with the slot 52 in the member 27 when the slide is moved forward but which does not fully align with said slot 52 in normal position of the slide as shown in solid lines in Fig. 5, the end of the arm 25 extending beyond the front end of said slot 59 in such normal position of the slide.

25 In the operation of the invention the frames 3, having the cloth 12 mounted thereon with the design or pattern 60, Fig. 2, top frame, adjusted thereon as best centered according to the eye of the operator, are advanced along the track on the table to come successively below the positioning points 45 carried by the member 27. As each frame is brought to a position below the member 27, as the middle frame in Fig. 2, the latch there- 30 of is released by raising the arm 25, whereupon the upper member of said frame will be raised away from the lower member thereof by the spring at the rear end of the frame, as already explained, leaving the cloth 12 free for accurate adjustment to register the design or pattern 60 with the points 45. During this adjustment of the cloth in the frame, the member 27 is supported above the upper member of the frame by 35 the spring at the rear end of said member 27 already described. After the adjustment has been made, the member 27 is moved downward by pressing upon the treadle 34. As the member 27 descends, the arm 25 on 40 the latch 21 is engaged with the slide 55, as indicated in dotted lines in Fig. 5 and in solid lines in Fig. 9. Said latch is thus held in retracted position until the upper member 50 of the embroidery frame is engaged with the lower member 5 thereof. Before the foot 45 of the operator is removed from the treadle, the slide 55 is moved by the finger piece 56 and against the tension of the spring 57 to release the arm 25, whereupon the spring 24 throws said arm to the horizontal position shown in solid lines in Figs. 1, 3 and 5, and engages the latch 21 with the lower member 5 of the embroidery frame, thereby locking the upper member 50 thereto.

60 It will be observed that by the means

herein shown and described a great number of frames may be quickly and accurately adjusted so as to insure the proper stitching or embroidering of the patterns alike. Heretofore it has been necessary to adjust the cloth 70 with the patterns centered merely by the eye, which was not accurate, or with a rule which consumed considerable time. It will also be noted that the number of the positioning points may be varied to suit requirements, 75 so that any design or pattern, no matter how simple or complicated, may be adjusted by the present device both accurately and quickly.

It should be noted that in addition to the 80 guides 37 and 39 at the rear end of the member 27, the front end of said member may carry a transverse bar 61, Figs. 2, 4 and 9, with turned down end portions 62 to fit between upstanding lugs 63 on the front end 85 of the upper member 50 of each frame. Said lugs 63 are preferably beveled on their inner faces, as at 64, for guiding the end portions 62 of the bar 61 on the member 27 into proper position between them. This centering 90 device also insures the proper positioning of the frames below the member 27, so that the positioning of the pattern in each frame will correspond exactly with the positioning of the pattern in the other frames. 95

As indicated in Fig. 1 at 65, if the piece of cloth to be embroidered is of considerable length, as may sometimes happen, especially where several designs are to be successively embroidered on the same piece, the extra 100 length of the cloth which is not clamped in the frame may be rolled up and supported between the extensions 14 and 17 of the side bars of the frame where it is out of the way and maintained in good condition during the 105 adjustment of the design or pattern.

Having thus described my invention, what I claim as new and desire to secure by Letters Patent of the United States is:

1. The combination with a support, of a 110 plurality of frames having pieces of cloth bearing similar patterns mounted thereon, means for guiding said frames successively along the support, and means arranged above the support and frames for positioning the 115 cloth in each frame in turn to accurately correspond with the positions of the other pieces of cloth in the other frames to insure the same arrangement of the pattern in each frame for stitching in an embroidery machine. 120

2. The combination with a support, of tracks thereon, a frame for clamping a piece of cloth bearing a design to be embroidered therein, guides on said frame to fit said 125 tracks, a positioning member mounted above said support and movable toward and away therefrom, means adjustable on said member for locating a given design accurately in the frame to insure the proper stitching thereof 130

in an embroidery machine, and means for actuating said positioning member.

3. The combination with a support, of a frame for clamping a piece of cloth bearing a design to be embroidered therein, a positioning member mounted above said support and movable toward and away therefrom, points adjustably mounted on said member for locating the outline of a given design 10 and centering the same in the frame, and means for accurately guiding said frame below said positioning member on the support.

4. The combination with a support, of a two-part frame for clamping a piece of cloth bearing a design to be embroidered between said parts, a positioning member mounted above said support and movable toward and away therefrom, means on said member for locating the design accurately in the frame 20 to insure the proper stitching thereof in an embroidery machine, means for guiding said frame on said support below said positioning member and means carried by the frame for releasably clamping the two parts thereof 25 together to permit adjustment of the cloth below the positioning member and the securing of said cloth in the frame after it has been properly positioned.

5. The combination with a support, of a frame for clamping a piece of cloth bearing a design to be embroidered therein, a positioning member arranged above said support and movable toward and away from the same, said member having a slot, bolts adjustible in said slot, locating points having shanks swiveled on said bolts for the purpose specified, and means for guiding said frame below said positioning member.

6. The combination with a support, of a frame for clamping a piece of cloth bearing a design to be embroidered therein, a positioning member arranged above said support and movable toward and away therefrom, means on said member for locating the design accurately in the frame to insure the proper stitching thereof in an embroidery machine, means for guiding the frame below said member on the support, and means to center said member on said frame.

50 7. The combination with a support, of a frame for clamping a piece of cloth bearing a design to be embroidered therein, a positioning member arranged above said support and hinged to swing toward and away therefrom, means on said member for locating the design accurately in the frame to insure the proper stitching thereof in an embroidery machine, means engaging the hinged end of said member for preventing lateral movement thereof, and means at the free end of said member to center it on the frame.

8. The combination with a support, of a frame for clamping a piece of cloth bearing a design to be embroidered therein, a posi-

tioning member arranged above said support and hinged to swing toward and away therefrom, means on said member for locating the design accurately in the frame to insure the proper stitching thereof in an embroidery machine, and means for centering the member on the frame comprising beveled lugs on the frame between which the free end portion of said member is adapted to be guided and fit when the member is swung down upon the frame.

9. The combination with a support, of a frame having members adapted to clamp a piece of cloth bearing a design to be embroidered between them, a positioning member arranged above said support and hinged to swing toward and away therefrom, means on said positioning member for locating the design accurately in the frame to insure the proper stitching thereof in an embroidery machine, means for guiding the frame below said positioning member on the support, a latch for locking the clamping members of the frame together, and means on the positioning member for releasably supporting said latch in unlocking position.

10. The combination with a support, of a frame having members adapted to clamp a piece of cloth bearing a design to be embroidered between them, a positioning member arranged above said support and hinged to swing toward and away therefrom, means on said positioning member for locating the design accurately in the frame to insure the proper stitching thereof in an embroidery machine, means for guiding the frame below said positioning member on the support, a latch for locking the clamping members of the frame together, an operating arm extending from said latch and means on said positioning member for releasably engaging said arm for supporting the latch in unlocking position.

11. The combination with a support, of a frame having members adapted to clamp a piece of cloth bearing a design to be embroidered between them, a positioning member arranged above said support and hinged to swing toward and away therefrom, means on said positioning member for locating the design accurately in the frame to insure the proper stitching thereof in an embroidery machine, means for guiding the frame below said positioning member on the support, a latch for locking the clamping members of the frame together, an operating arm extending from said latch, and a slide on the positioning member to releasably engage said arm to support said latch in unlocking position.

In testimony whereof I have signed my name to this specification.

WILLIAM KOLLER.
